United States Patent Office

Des. 185,342
Patented June 2, 1959

185,342

RUG DISPLAY STAND

Leon H. Best, Galva, Ill., assignor to John H. Best & Sons, Inc., Galva, Ill., a corporation of Illinois

Application August 29, 1958, Serial No. 52,454

Term of patent 14 years

(Cl. D80—9)

Fig. 3

Fig. 4

Fig. 5

Fig. 1 is a side perspective view of a rug display stand embodying my design;

Fig. 2 is a rear perspective view on a slightly enlarged scale of the stand shown in Fig. 1.

Fig. 3 is a side elevation of the stand shown in Fig. 1;

Fig. 4 is a top plan view of the stand shown in Fig. 1; and

Fig. 5 is a front elevation of the stand shown in Fig. 1.

I claim:

The ornamental design for a rug display stand, substantially as shown.
